UNITED STATES PATENT OFFICE.

OTTO SPEEHR, OF BROOKLYN, NEW YORK.

WASHING APPARATUS.

1,265,826.

Specification of Letters Patent. Patented May 14, 1918.

Application filed December 31, 1917. Serial No. 209,807.

To all whom it may concern:

Be it known that I, OTTO SPEEHR, a citizen of the United States, residing at Brooklyn, in the county of Kings and State of New York, have invented certain new and useful Improvements in Washing Apparatus, of which the following is a specification.

This invention relates to a device used in connection with washing machines, and embodies a new apparatus for preparing liquid or solution for washing purposes.

It is well known that the material going to laundries to be washed is often in need of disinfecting as well as cleansing, and the present invention provides means for accomplishing these purposes.

Specifically, it provides means for introducing a disinfecting vapor, such as a vapor of kerosene, into a washing machine, under high pressure and temperature, whereby it is thoroughly distributed through all parts of the washing liquid.

In addition to its disinfecting action, kerosene vapor has a cleansing action, and also serves to preserve the parts of such machinery.

The invention embodies a vaporizer and an atomizer connected thereto, and associated with an injector which is operated by steam and delivers the vapor in a finely divided condition to the hot water supply of the washing machine.

The accompanying drawing is a sectional view of the apparatus.

Referring to this drawing, 6 indicates a vaporizing tank of considerable capacity. This is inclosed by steam jacket 7 to which steam is supplied through an inlet 8, having an outlet 9 at the bottom which may lead to a trap. Kerosene or other disinfecting fluid may be poured into the tank through a pipe 10 at the top, and water pressure may be supplied through a pipe 11 at the bottom, which also serves as a drain.

The pipe 10 is provided with a vapor outlet pipe 12 having a check valve 13 therein, and connected to the bottom of a receiving tank or vessel 14 of relatively small capacity. This vessel is connected to an injector by a pipe 15 which dips into the vessel to nearly the bottom thereof.

The injector comprises a casing 16 which may screw into the neck of the tank, and in this casing 16 is a nozzle 17 supported by a partition 18, the whole forming a passage leading from the pipe 15 to the annular

space around the jet nozzle 17. Steam under pressure is supplied to the injector through a pipe 19 controlled by a valve 20, and there is a passage 21 leading from the inlet side of the injector casing through a small port 22 into the top of the tank 14 so that the vapor in the tank is under pressure. The discharge outlet from the injector is connected by a pipe 23, having a valve 24, to a water supply pipe which leads to the washing machine not shown. The valves 20 and 24 are connected by a link 26 so that they open and close together. A three-way valve 27 controls the filling pipe of the vaporizer tank 6, and the outlet to the connecting pipe 12.

In the operation of the apparatus kerosene or other disinfecting liquid is put in the tank 6, and put under some pressure through the pipe 11, as by water admitted to the tank. Steam is admitted to the surrounding jacket and the kerosene is thereby vaporized, and this vapor is forced through the pipe 12 into the receiver 14. By opening valves 20 and 24 the injector acts to draw the vapor from the receiver and it is entrained by the steam jet and discharged at a high velocity into the hot water supply pipe and passes thence to the washing machine. The injector action is assisted by the steam pressure admitted from the steam line through the port 22.

The water thus supplied to the washing machine becomes impregnated with the vapor of kerosene and this has a disinfecting action on the material being washed and also serves to save soap, as suds are much more easily produced in water charged with kerosene vapor. The vapor being in a highly heated condition mixes readily and effectively with the water, and is much superior to any attempted mixing of the same when in liquid form.

When the injector action is stopped the receiver 14 will be refilled by vapor forced from the vaporizing tank by the pressure admitted thereto.

The invention is not limited to the particular apparatus shown, but may be modified in various ways.

I claim:

1. In a washing apparatus, the combination of a heated vaporizer for a disinfecting or cleansing agent, and an injector connected to said vaporizer and adapted to inject vapor therefrom into a washing machine.

2. In a washing apparatus, the combination of a heated vaporizer for a disinfecting or cleansing agent, a tank for vapor connected thereto, and an injector connected to the tank and adapted to inject vapor therefrom into a water supply to a washing machine.
3. The combination of a vaporizer, a receiver connected thereto, an injector having a steam supply pipe thereto and connected to a water supply line, and a branch passage from the steam pipe into the receiver, to heat the vapor therein and maintain same under pressure.
4. The combination of a heated vaporizer, a vapor pressure tank connected thereto, a check valve between the vaporizer and the

tank, and an injector connected to the tank and adapted to inject fluid therefrom into a water supply.

5. In a washing apparatus, the combination of a vaporizer for a disinfecting or cleansing agent, provided with means to create pressure therein, a tank for vapor connected thereto and adapted to be supplied with vapor therefrom in consequence of such pressure, and means to inject vapor from said tank into a washing machine.

In testimony whereof, I affix my signature in presence of two witnesses.

OTTO SPEEHR.

Witnesses:
